UNITED STATES PATENT OFFICE.

ADOLF A. STEINHILBER, OF ROCK ISLAND, ILLINOIS, ASSIGNOR TO ARTISTA PIANO
PLAYER COMPANY, OF MILAN, ILLINOIS, A CORPORATION OF ILLINOIS.

TEMPO-REGULATOR AND REWINDING MECHANISM FOR PIANO-PLAYERS.

1,141,283.

Specification of Letters Patent.

Patented June 1, 1915.

Application filed October 11, 1911. Serial No. 653,983.

To all whom it may concern:

Be it known that I, ADOLF A. STEINHILBER, a citizen of the United States, residing at Rock Island, in the county of Rock Island 5 and State of Illinois, have invented certain new and useful Improvements in Tempo-Regulators and Rewinding Mechanism for Piano-Players, of which the following is a specification.

10 This invention relates to improvements in tempo regulators and rewinding mechanism for mechanical musical instruments particularly of the type in which there is employed a pneumatic motor operated by exhausting 15 the air therefrom and which exhaust mechanism is also connected with the wind chest for exhausting the latter, and one of the objects of the present invention is to provide an improved apparatus of this character, 20 having means whereby the exhaust may be cut off from the wind chest and directed entirely to the motor, to increase the speed of operation of the latter and at the same time prevent the operation of the parts controlled 25 by the suction in the wind chest.

30 A further object is to provide an improved apparatus of this class having means whereby the record may be advanced or rewound without actuating the note sounding instrumentalities.

35 A further object is to provide an improved apparatus of this class which will be simple, durable and cheap in construction and effective and efficient in operation.

40 To the attainment of these ends and the accomplishment of other new and useful objects as will appear, the invention consists in the features of novelty in substantially the construction, combination and arrangement of the several parts hereinafter more fully described and claimed and shown in the accompanying drawings, showing an embodiment of the invention and in which—

45 Figure —1— is a front elevation with parts broken away, of an improved apparatus of this class constructed in accordance with the principles of this invention. Fig. 1^a is a view of a detail, partly in section. Fig. —2— is a detailed sectional view taken 50 on line —2—2— Fig. —3—. Fig. —3—, is a view partly in elevation, partly in section, and with parts broken away of the governor or controller mechanism. Fig. —4— is a detailed sectional view on line —4—4— Fig. 55 —3—. Fig. —5— is a detailed sectional

view taken on line —5—5—, Fig. —3—. Fig. —6— is a top plan view of the valve box for controlling the suction in the wind chest. Fig. —7— is a sectional view on lines —7—7—, Fig. —6—. Fig. —8— is a front elevation of Fig. —6—. Fig. —9— is a detailed view taken on line —9—9—, Fig. —1—.

60 Referring more particularly to the drawings and in the present exemplification of this invention, the numeral —10— designates the wind chest which is arranged in any suitable manner within the casing of the instrument, a portion of which latter being indicated in Fig. —1—, and to which is connected the pneumatics 10^a which latter operate the note-sounding instrumentalities designated generally by the reference numeral 10^b, and which pneumatics are connected with the tracker board 12 by the tubes 10^c 70 in a manner well known in devices of this character.

75 Supported by the wind chest in any suitable or convenient manner is a frame designated generally by the reference numeral 80 —11— and in this frame is arranged the tracker board —12— on one side of which is arranged the record spool —13—, while the record spool —14— is arranged on the opposite side of the tracker board, the latter spool 85 —15— as it passes over the tracker board —12— from the roll —13—.

90 The motor for feeding the record sheet is designated generally by the reference numeral —16—. This motor is of the pneumatic type and embodies a crank shaft —17— and controlling valves —18—. The crank shaft is preferably arranged above the motor as shown and is journaled in suitable 95 bearings, one end of the shaft being detachably connected with a stub shaft —19—, journaled preferably in a supplementary frame —20— supported by the frame —11—. Connected with this stub shaft 100 —19— is an elongated pinion gear —21—, with which a traveling gear —22— measures. This gear —22— is mounted upon a shaft —23— which is connected in any suitable manner with the shaft of the spool 105 —14—.

110 The gear is adapted to be shifted longitudinally on the shaft —23— preferably by means of a lever —24— pivoted intermediate its ends as at —25— with one end con-

nected with a collar —26— secured to the gear —22— for rotation therewith. The gear —22— is provided with a lateral projection or pin —26^a— which is adapted to enter a recess in a collar —27— which latter is secured to the shaft —23— for rotation therewith, so that when the projection —26^a— is seated within the aperture within the collar and the gear —22— rotated, the shaft —23— together with the spool —14— will also be rotated to draw the record from the spool —13— on to the spool —14—. Journaled in the supplementary frame —20— is another shaft —28— to which is secured a sprocket wheel —29—, this sprocket wheel is connected by means of a sprocket chain —30— with another sprocket wheel on the shaft —31—, which latter is detachably connected as at —32— with a trunnion on the spool —13—. The other trunnion —32— of the spool —13— is journaled in a suitable bearing, —33—, and an elastic member —34— is provided which engages the end of the bearing —33— and tends normally to hold the spool —13— in position.

On the shaft —28—, is a gear —35— which is connected with the sprocket —29— for rotation therewith and is so arranged with respect to the gear —22—, that the latter may be moved into and out of mesh therewith. The pinion —21— however, is of such a length that the gear —22— in any of its positions will always remain in mesh therewith. Thus it will be seen that when the gear —22— is moved out of mesh with the gear —35—, and the projection —26^a— is seated in the recess in the collar —27—, the spool —14— will be connected with the motor shaft —17— through the medium of the pinion —21— and gear —22—. In this position the spool —13— will be disconnected from the motor and when the motor is operated the record sheet —15— will be drawn across the tracker board —12— and on to the spool —14—. Should the gear —22— be shifted so that it will mesh with the gear —35—, then the spool —14— will be disconnected from the motor shaft —17— and the spool —13— will be connected with the motor to be operated thereby through the medium of the sprocket chain —36—, to rotate the roller —13— and thereby rewind the record sheet —15— back on to the spool —13—.

The gear —22— is shifted manually at the will of the operator and for this purpose there is provided an operating lever —36—, which is arranged in a convenient position for the operator, preferably at the front and center of the instrument. This lever —36— is pivotally supported, preferably intermediate its ends as at —37— and one end is connected by means of a link —38— to an arm —39— on a rock shaft

—40—. Another arm —41— on the rock shaft is connected by means of a link —42— to one arm of a bell crank lever —43— which latter is pivotally supported as at —44—. To the other arm of the bell crank —43— is connected a slide bar or rod —45— which is supported for such movement in suitable bearings and arranged on this slide bar are spaced arms or projections —46— —47—, between which the free extremity —48— of the lever —24— projects. These arms or projections —46— —47— are so spaced from each other that when the bar or rod —45— is moved longitudinally in one direction or the other by the manipulation of the lever —36—, they will respectively engage the extremity —48— of the lever —24— to rock the latter about its point of pivotal support —25— and thereby shift the gear —22— in the manner already described. These arms —46— —47— are also so spaced from each other as to permit a movement of the rod —45— without engaging the lever —24— for a purpose as will be set forth. An elastic member —49— is provided, one end of which is connected with the lever —48— and the other end is anchored to a suitable fixed support and tends normally to move the member —24— in a direction to shift the gear —22—, to lock the spool —14— for rotation by the motor to advance the record, and a stop —50—, is also provided for limiting the movement of the lever —24— under the influence of the elastic member —49—.

The note sounding instrumentalities are connected in the ordinary and usual manner (and therefore not necessary to illustrate,) with the wind chest —10— and also with the apertures in the tracker board —12— and in order therefore to prevent the operation of these instrumentalities, and consequently the sounding of the notes during the rewinding of the record —15—, there is provided valve mechanisms which cut off the suction from the wind chest during this rewinding operation. This valve mechanism embodies a housing designated generally by the reference numeral —51— which is connected or has communication with the wind chest in any suitable manner so that the air will be exhausted from the wind chest through this housing by means of a tubular member —52—, which is connected with the outlet —53— of the housing and also with the equalizer of one of the pumper bellows 52^a. This housing —52— is provided with a valve seat —54— intermediate the inlet and the outlet of the housing and a valve —55— is provided which co-operates with the valve seat. When the valve is moved off its seat into the position shown in Figs. —6— and —8—, the tubular member —52— will be connected with the wind chest to exhaust the latter,

but when the valve —55— is seated, the wind chest will be closed to the pumpers, and inasmuch as the air cannot then be exhausted from the wind chest, the note sounding instrumentalities will not be actuated. In order to simultaneously actuate this valve —55— when the gear —22— is shifted, the valve is connected preferably with the slide bar or rod —45— through the medium of the extension —56— which is connected with the slide bar and also with a crank arm —57— on a rock shaft —58— to which latter the valve —55— is connected. This crank arm —57— is adjustably connected with the rock shaft —58— by means of a suitable fastening device —59— so that the crank arm may be adjusted to any suitable position on the shaft.

The extension —56— is flexibly connected with the crank arm —57— through the medium of a loop —60— (see particularly Fig. —6—) through which loop a pin —61— on the crank arm —57— passes and the length of the extension —56— is such that when the lever —36— is moved to the right in Fig. —1—, to cause the gear —22— to connect the spool —14— with the motor for moving the record sheet and playing the instrument or in playing position, the movement of the bar —45— and extension —56—, will result in the extremity of the loop —60— engaging the pin —61— to rock the shaft —58— and thereby unseat or open the valve —55—. It is necessary in the playing position that the valve —55— be held open, because of the pressure or suction which operates on the left hand side of the valve (Fig. —6—) and which tends normally to close the valve. By the provision of the loop —60— the lever —36— may be moved into upright or intermediate position or to a position which will permit the valve —55— to close by the suction and also to permit the lever —36— to be moved into a position to effect a rewinding of the record without opening the valve —55— and thus prevent the operation of the note sounding instrumentalities during the rewinding operation. Inasmuch as the suction is on the left side of the valve 55 (Fig. 6) it would close were it not for the fact that it is held open by the loop 60 of the rod 56 engaging the pin 61, and it is desirable to hold this valve open when the shunt passage from the motor is properly opened. This shunt passage hereinafter described, when open, connects the motor directly with the pumpers. Thus it may be used as an auxiliary to increase the speed of the motor during portions of the playing operation, and of course the valve 55 must be open under this condition.

The speed of the motor during the playing operation or the tempo is controlled or regulated through the medium of governor

mechanism which will now be described, reference being had particularly to Figs. —2— to —5—.

Mounted upon a suitable fixed support preferably the wind chest —10— is a housing 70 designated generally by the reference numeral —62— which housing is provided with a chamber —63— having communication as at —64— with the exhaust passage of the motor —16—, and this chamber —63— is 75 connected by means of a passage —64— with a governor pneumatic —65— through the passage —66— of the pneumatic which communicates with the passage —64—. A slide valve —67— is mounted to move in suitable 80 guides —68— to control the passage —64— and through the manipulation of this valve —67— the passage —64— may be opened to a greater or less extent and inasmuch as the suction from the motor, during the play- 85 ing operation is through this passage —64—, it will be manifested the speed of the motor may be controlled by the manipulation of this valve —67— in a manner to be herein- 90 after described.

The pneumatic —65— embodies a movable element or member —69— which latter is adapted to be moved in one direction to expand the pneumatic, preferably by means of an elastic member —70—, one end of which is 95 connected to an arm or extension —71— projecting beyond the smaller end of the pneumatic and which arm is connected with the movable member of the pneumatic and the other end of the elastic member is anchored 100 to a suitable fixed support. This elastic member tends normally to expand the pneumatic and when the pneumatic is collapsed it is against the action or tension of this elastic member. The pneumatic also 105 has communication with a suction or exhaust pipe —72— which latter leads to the equalizer of one of the pumper bellows 72^a and also communicates with a passage —73— which latter has communication with a pas- 110 sage —74— leading through the housing —62— out of communication with the chamber —63—. The passage —74— has com- 115 munication with the pneumatic through the medium of the passage —75— and a valve —76— is provided for controlling the pas- 120 sage —75—. This valve —75— is arranged to be seated against the suction in the pipe —72— and is opened automatically by the movement of the movable member —69— and for this purpose there is provided a lever —77— which is fulcrumed as at —78—, one end of the lever is suitably connected with the stem of the valve —76— and the other end of the lever is arranged adjacent 125 the projection —79— carried by the movable member —69— of the pneumatic. This projection —79— is normally held out of contact with the lever —77— when the pneumatic —65 is open or expanded, so that the 130

valve —76— will be normally held open by the air pressure on the back of the valve. When, however, the pneumatic —65— is collapsed, the projection —79— engages the lever —77— to seat or close the valve. The projection —79— is connected with the slide —80— which latter is adjustably connected with the movable member —69— so that the projection may be adjusted, with respect to the fulcrum of the lever —77— and thereby vary the time of operation for closing of the valve —76—. The passage —74— also has communication with the chamber —73— through the medium of the passage —81— and a valve —82— is provided for normally closing this passage —81— to cut off communication of the passage —74— with the chamber —73—.

The rock shaft —83— is flexibly connected with the valve —82— in any suitable manner to permit the pressure or suction to seat the valve —82— closely. This connection may be formed in any suitable manner. A simple and efficient manner comprises a fastening device —84— which is threaded as at —85— into the valve —82— and is provided with an enlarged portion —86— projecting into an aperture —87— in a reduced portion —88— of an arm of the rock shaft —83—. When this valve —82— is closed, and suction is created through the pipe —72—, and the valve —67— is adjusted to open the passage —64—, the direction of the air will be from the motor through the passage —64— into the chamber —63—.

Air will pass from the chamber —63— into the pneumatic —65— through the passage —66—. When the suction acting begins to collapse the pneumatic —65— the valve 76 will be correspondingly adjusted and the air will pass from the pneumatic through the passage —75— into the passage —74— from the passage —74— into the passage —73— and out through the pipe —72—. This is the course of the air during the playing operation. If the passage —64— is wide open, the motor will be running at its highest speed and therefore in order to control the speed of the motor all that is necessary is to adjust the valve —76—. This is accomplished manually and for this purpose there is provided a second operating lever —89— which is arranged preferably adjacent the lever —36— and this lever —89— is fulcrumed as at —90— intermediate its ends.

One end of the lever is connected by means of a link —91— with an arm on a rock shaft —92—. The other arm of the rock shaft is connected by means of a link —93— with one arm of a bell crank lever —94—, the latter being fulcrumed as at —95—. The other arm of the bell crank is connected by means of a connection —96— with the tempo indicating finger —97—

which is movable over the tempo index —98—.

Pivottally mounted preferably upon one wall of the housing —62— is a crank —99— to which is connected an arm —100— having a bifurcated extremity —101— into which bifurcation a pin —102— on the connection —96— projects. The other end of the crank —99— projects into a recess —103— on the slide valve —67— so that when the crank —99— is rocked about this point of pivotal support, the valve —67— will be moved in its guides to open or close the passage —64— at the will of the operator and according to the direction of movement of the valve. Thus when the lever —89— is manipulated, the bell crank lever —94— will be rocked and this rocking movement of the bell crank will rock the crank —99— moving the valve —67— and also the tempo indicating finger —97—.

During the playing operation, as has been before stated, the valve —82— is closed and the air circulates through the governor in a tortuous passage out of the pipe —72—. When it is desired to rewind the record on to the spool —13—, and to operate the motors —16— as rapidly as possible, it is advisable to establish a direct communication of the air from the motor around the governor pneumatic —65— and through the chamber —63— to the pipe —72—. This is accomplished by opening the valve —82— and when opened the air will seek the shortest passage to the pipe —72— even though the passage —64— is open. When the valve —82— is opened, the air will pass directly from the chamber —63— through the passage —81— into the passage —73— and thence out through the pipe —72—. In order therefore to open this valve —82— simultaneously with the shifting of the gear —22—, to a rewinding position, there is provided on the shaft —83— a projecting arm —104— which extends between two projections —105—, —106—, connected with the slide bar —45— and which projections —105—, —106— are adapted to engage and move the arm —104— to rock it in one direction or the other to open or close the valve —82— according to the direction of movement of the rod —45—.

It is thought that the operation of this improved apparatus will be clearly understood from the foregoing description, but briefly stated it is as follows: When the lever —89— is shifted to the right (Fig. —1—) the connection —96— is caused to move horizontally in the same direction through the medium of the intermediate connecting mechanism. The movement of this connection —96— by reason of the pin —102— projecting into the bifurcated extremity —101— of the arm —100—, will move the valve —67— in the opposite direc-

tion. This valve opens and closes the passage —64— which regulates the passage of the air from the motor to the pumpers. When the passage —64— is opened to its fullest extent the motor has its greatest speed and the speed of the motor is reduced by moving the lever —89— in the opposite direction, thus moving the valve —67— to the right (Fig. —3—) to reduce the area of this passage. At the same time the tempo finger or indicator —97— will be correspondingly adjusted with respect to the index —98—. By throwing the top of the lever —36— to the extreme left, (Fig. —1—) the slide bar —45— and connection —56— will be shifted, the lug or projection —106— on the slide —45— will engage the arm —104— to rock the shaft —83— and open the valve —82— at the same time the loop —60— with the connection —56— will permit the valve —55— to close and thereby shut off suction in the wind chest. With the valve —82— wide open, the motor will be running at its highest speed inasmuch as the suction will be around the governor. At the same time, or at the time when this lug —106— opens the valve —84—, the lug —46— will engage the extremity —48— of the lever —24— to shift the latter and thereby move the gear —22— into mesh with the gear —35— which will connect the spool —13— with the motor shaft thereby effecting a rewinding of the record from the spool —14— to the spool —13—. When the lever —36— is drawn to the extreme right hand position (Fig. —1—) the lug —105— will engage the arm —104— to close the valve —82— at the same time the arm —47— on the slide —45— will engage the extremity —48— of the lever —24— to shift the gear —22— out of mesh with the gear —35— and into a position to connect the spool —14— with the motor shaft. The loop —60— on the connection —56— will during this movement of the slide —45— open the valve —55— to permit the air to be drawn from the wind chest. In the event that it is desired to advance the record sheet without actuating the note sounding instrumentalities the lever —36— may be moved to an approximately upright or intermediate position which will cause the slide —45— and the connection —56— to move in the same direction. This movement of the slide —45— will cause the projection —106— to engage the arm —104— to partially open the valve —82—, thus allowing an additional passage for the air from the motor and the chamber —63—, to produce a more rapid movement of the motor. During this operation or adjustment of the slide —45—, the arm or projection —46— thereon moves toward but does not engage the extremity —48— of the lever —24— and the latter will be held in this position by the elastic member —49—, thus leaving the mechanism in position for advancing the record sheet over the tracker board to be wound on the spool —14—. The movement of the connection —56— to the left permits the valve —55— to close, thus shutting off communication between the wind chest and the pumpers with the result that the record sheet will move forwardly but the note sounding instrumentalities will not be actuated obviously. The front wall of the chamber —63— may be removably secured in position thereby permitting ready access to the interior of the mechanism housed therein without dismantling the other parts.

What is claimed as new, is:

1. In a tempo regulator, the combination of a motor, air exhausting means connected with the motor and embodying a passage, a governor pneumatic arranged in the passage and through which the air passes, means controlled by the action of the pneumatic for controlling the passage, means for varying the time of operation of the last said means relative to the movement of said pneumatic, a regulator valve for also controlling the passage, means for controlling the last said valve, a shunt passage for the air from the motor around said pneumatic, and means for controlling said shunt passage.
2. In a tempo regulator, the combination of a motor, air exhausting means connected with the motor and embodying a passage, a pneumatic arranged in said passage and through which the air passes, said pneumatic embodying a movable member, means connected with said member and tending normally to expand the pneumatic, a valve controlled by said movable member and adapted to close the passage, means whereby the movement of said member to expand the pneumatic will control the valve, means for varying the time of the opening of said valve relative to the movement of said member, means for controlling the passage of air into the pneumatic, a shunt passage for the air around the pneumatic, and means for controlling the shunt passage.
3. In a tempo regulator, the combination of a motor, air exhausting means therefore embodying a passage for the air, a collapsible pneumatic in the passage and through which the air passes, said pneumatic embodying a movable member, a valve for controlling the passage, adjustable means between the valve and movable member of the pneumatic, whereby the movement of said member will actuate the valve, means tending normally to expand the pneumatic, a shunt passage for the air from the motor around the pneumatic and connected with the first said passage, and a manually controlled valve for connecting and disconnecting the said passages.

4. In a tempo regulator, the combination of a motor, air exhausting means therefor embodying a passage for the air, a collapsible pneumatic in the passage and through which the air passes, said pneumatic embodying a movable member, a valve for controlling the passage, an adjustable means between the valve and movable member of the pneumatic, whereby the movement of said member will actuate the valve, means tending normally to expand the pneumatic, a shunt passage for the air from the motor around the pneumatic and connected with the first said passage, a manually controlled valve for connecting and disconnecting the said passages, and a third valve, the latter being adapted to control the passage of the air into the pneumatic.

5. In a tempo regulator, the combination of a motor, air exhausting means therefor embodying a passage for the air, a collapsible pneumatic in the passage and through which the air passes, said pneumatic embodying a movable member, a valve for controlling the passage, adjustable means between the valve and movable member of the pneumatic, whereby the movement of said member will actuate the valve, means tending normally to expand the pneumatic, a shunt passage for the air from the motor around the pneumatic and connected with the first said passage, a manually controlled valve for connecting and disconnecting the said passages, a third valve, the latter being adapted to control the passage of the air into the pneumatic, and manual means for controlling the last said valve at will.

6. A tempo regulator embodying in combination an air exhaust passage, a collapsible pneumatic arranged in the passage and through which pneumatic the air passes, said pneumatic embodying a movable member, a valve for closing the passage, an actuating lever for the valve arranged within the pneumatic and connected with the valve, means operated by the movable member of the pneumatic adapted to engage the lever to operate the same to control the valve, and means for expanding the pneumatic.

50. 7. A tempo regulator embodying in com-

bination an air exhaust passage, a collapsible pneumatic arranged in the passage and through which pneumatic the air passes, said pneumatic embodying a movable member, a valve for closing the passage, an actuating lever for the valve arranged within the pneumatic and connected with the valve, means adjustably supported by the movable member of the pneumatic, adapted to engage the lever to operate the same to control the valve, and means for expanding the pneumatic.

8. A tempo regulator embodying in combination an air exhaust passage, a collapsible pneumatic arranged in the passage and through which pneumatic the air passes, said pneumatic embodying a movable member, a valve for closing the passage, an actuating lever arranged and fulcrumed within the pneumatic, and connected with the valve for actuating the latter, and means carried by the movable member of the pneumatic and adjustable with respect thereto toward and away from the fulcrum of the lever for operating the lever and for varying the time of actuation of the valve thereby.

9. A tempo regulator embodying in combination an air exhaust passage, a collapsible pneumatic arranged in the passage and through which pneumatic the air passes, said pneumatic embodying a movable member, a valve for closing the passage, an actuating lever arranged and fulcrumed within the pneumatic, and connected with the valve for actuating the latter, means carried by the movable member of the pneumatic and adjustable with respect thereto toward and away from the fulcrum of the lever for operating the lever and for varying the time of actuation of the valve thereby, and means tending normally to expand the pneumatic to operate the valve to control said passage.

In testimony whereof I have signed my name to this specification, in the presence of two subscribing witnesses, on this 4th day of October, A. D. 1911.

ADOLF A. STEINHILBER.
